UNITED STATES PATENT OFFICE.

WILLIAM O. BUNNELL AND QUINCY A. GATES, OF WILKES-BARRE, PENNSYLVANIA.

GARBAGE-RECEPTACLE.

1,239,348.

Specification of Letters Patent. Patented Sept. 4, 1917.

Application filed September 13, 1916. Serial No. 119,874.

To all whom it may concern:

Be it known that we, WILLIAM O. BUNNELL and QUINCY A. GATES, citizens of the United States, and residents of Wilkes-
5 Barre, in the county of Luzerne and State of Pennsylvania, have invented certain new and useful Improvements in Garbage-Receptacles, of which the following is a specification.

10 The present invention relates to the class of metallic shipping and storing vessels and has particular reference to new and useful improvements in garbage receptacles.

15 The primary object of our invention is to provide a new and improved type of garbage receptacle which is for all practicable purposes odorless.

20 Another object of our invention is to provide a garbage receptacle having a novel type of closure adapted to permit one to deposit garbage within the receptacle and also serving to close the receptacle after garbage has been deposited therein to prevent the escape of odors and exclude insects such as 25 flies and the like from access to the contents of the receptacle.

25 A further object of our invention is to provide a garbage receptacle of the class described which is simple in construction, 30 strong and durable, cheap to manufacture and effective in use.

35 Other objects and advantages to be derived from the use of our improved garbage receptacle will appear from the following detail description and the claims, taken with an inspection of the accompanying drawing, in which:

40 Figure 1 is a side elevational view of a garbage receptacle embodying the improvements of our invention; and

Fig. 2 is a vertical sectional view taken on the line 2—2 of Fig. 1 looking in the direction of the arrow.

45 Referring more particularly to the drawing, wherein similar characters of reference designate like and corresponding parts throughout the various views, 1 designates the body of our improved garbage receptacle, the same having the usual bottom 2 therein.

50 The body of the receptacle is open at the upper end and is provided with a closure 3 hinged at 4 to the peripheral wall of the body. The closure 3 is provided with a handle 5 which facilitates opening of the 55 same.

A supplemental opening 6 is provided in

the peripheral wall of the body 1 adjacent the upper free end thereof, said opening being closed by a curved door 7 having a knob or handle 8 and mounted in a guide frame 9 carried by the outer surface of the body 1. A housing 10 is mounted within the body, said housing having the bottom open and formed with an offset portion 11. A shaft 12 is mounted transversely of the body, extending through the housing the free end of the shaft being bent as at 13 to form a crank portion having a handle 14 thereon. A rotatable partition 15 is carried by the handle and movable with the shaft 12, said 65 partition having wing portions 16 oppositely disposed and formed with flanges 17. The curved flanges and the offset 11 engage to render the receptacle practically airtight. The normal closed position of the partition 70 is as shown in Fig. 2, and assuming that it is desired to deposit garbage or the like within the receptacle the door 7 is opened and the garbage poured upon the partition, the weight of the garbage causing the partition to swing to a vertical position depositing the contents thereof into the receptacle. The partition is moved to closed position 75 by means of the crank 14.

We desire to lay particular stress upon 80 the simplicity of the device of our invention and it will be readily seen that the escape of odors from the receptacle is practically impossible when the closure partition is in the position shown in Fig. 2. Attention is also 85 directed to the fact that the receptacle of our invention need not be employed strictly as a garbage can since the same may be as readily adapted for use as an ash can or any other container of the class referred to. It 90 will be apparent that the housing occupies 95 but one third of the diameter of the body 1.

From the above description taken in connection with the accompanying drawing, it is thought that a clear and comprehensive 100 understanding of the construction, operation and advantages of our invention may be had, and while we have shown and described the device as embodying a specific structure, we desire that it be understood that such 105 changes may be made in said structure as do not depart from the spirit and scope of the invention as claimed.

Having thus fully described our invention, what we claim as new and desire to secure by Letters Patent, is:—

1. In a garbage receptacle the combina-

tion of the body having an inlet opening adjacent the upper end thereof, a closure for said opening, a housing in said body communicating with the opening and having an open bottom, a rotatable partition arranged across said open bottom, means for rotating said partition from outside of the body, an offset portion on the lower edge of the housing, and flanges on said partition adapted 10 for engagement with the off-set portion of the housing, and the adjacent wall of the casing when the partition is horizontally disposed to make the device normally air tight.

15 2. A garbage réceptacle of the class described comprising a cylindrical body hav-

ing an open top, a closure for the same, said body being provided with the supplemental inlet opening adjacent its upper edge, a closure for said inlet slidably mounted on 20 the outer wall of the body, a housing within the body having an open bottom and communicating with the inlet, a rotatable shaft extending through said body, a crank on the outer end of the same, and a partition on 25 said shaft adapted to form a closure for the open bottom of the housing.

In testimony whereof, we affix our signatures hereto.

WILLIAM O. BUNNELL.
QUINCY A. GATES.
